SHOULDER PAD

Florence B. Zacks, Columbus, Ohio

Original application December 21, 1946, Serial No. 717,637, now Patent No. 2,422,161, dated June 10, 1947. Divided and this application May 12, 1947, Serial No. 747,460

2 Claims. (Cl. 2—268)

1

This invention relates to shoulder pads and more particularly to shoulder pads adapted to be worn in connection with garments to enlarge or vary the contour in accordance with the prevailing mode.

This application is a division of my copending application Serial No. 717,637, filed December 21, 1946, now Patent No. 2,422,161, granted June 10, 1947.

The general object of the invention is to provide a novel and improved shoulder pad of the class described which is of pliant construction whereby it may be fitted or molded to conform to the contour of the shoulder of the individual wearer.

Although it will be perceived from the detailed disclosure of the novel pad that its use is not to be so circumscribed or limited, it may be mentioned that the pad is particularly adapted for use as an independently-supported article of apparel, which is not attached to the garment to which it gives shape. One example of this type of pad is designed to be detachably secured by various means to the shoulder straps of an undergarment, and this manner of attachment has a number of advantages over the conventional sewed-in type of pad, among which is the overcoming of difficulties of removal and restoration when the garment is cleaned or pressed.

Another advantageous feature of the invention lies in the fact that the padding material in the present pad may be made softer and lighter than usual in view of the shape-maintaining reinforcing means employed. Furthermore, the reinforcing or supporting frame is pliant, although slightly resilient, and may be bent to shape during the conforming or molding of the pad to the individual shoulder, and remain in such shape during wear.

A further object of the invention is to provide a shoulder pad which is light, inexpensive, and adaptable to a large variety of garments.

Other objects and features of novelty will be apparent from the following specification when read in connection with the accompanying drawings in which one embodiment of the invention is illustrated by way of example.

In the drawings,

Figure 1 is a bottom plan view of a shoulder pad embodying the principles of the present invention;

Figure 2 is a sectional view of the pad taken on line 2—2 of Figure 1; and

Figure 3 is a view in perspective of the pad shown in Figure 1.

2

In order to more fully disclose the invention, a particular embodiment thereof is shown in the accompanying drawings, in which there is illustrated a pad 10 filled with a fibrous material 11. 5 The pad 10 may be of the usual or conventional shape given to most pads of this description and the fibrous material 11, while generally extremely light and fluffy in nature, may be composed of any one of a mixture of the materials now 10 in common use in producing pads for garments. A support or shape-maintaining member 12 is positioned within the pad 10 as shown in Figures 1 and 2. In the particular embodiment disclosed herein, this skeletal support member 12, as shown, 15 is a metal wire having a somewhat triangular outline and having a curved shape along one edge of the triangle. There are a variety of materials which may be employed as a support member and which may be fashioned in a variety of 20 shapes. The support member 12 functions both as an element for imparting form to the pad 10 as well as an element to retain the shape of the pad when subject to the tension of straps or 25 tapes when such are used, as hereinafter described. It is also most desirable for all uses that the support member 12 have a certain amount of resiliency or springiness, but it is essential that it be pliant so as to be yet capable 30 of being bent in order to shape the pad to fit the shoulder and to remain in the configuration into which it is bent so as to give the desired outline to the garment.

On the under side 14 of the pad 10, a pair of straps or tapes 15—15 is shown, each of which 35 has one end sewed to the under side 14, as shown at 16, and the other end, as shown at 18, detachably fastened to the under side 14 of the pad by means of suitable snap fasteners. The straps or tapes 15—15 are preferably composed 40 of an elastic material and the snap fasteners 18 are so positioned relative to the sewed end of the tapes 15—15 that it is necessary to stretch the tapes in order to fasten them on the pad, thus tensioning them in position.

45 As in the case of the usual shoulder pad of this description, the pad shown in Figures 1 and 2 contains a maximum amount of fibrous material 11, or padding, at the outer shoulder end 19, the padding decreasing gradually to a 50 minimum at the inner end 20 which is disposed nearest the neck. In order to position the shoulder pad on the shoulder of the wearer, the garment strap 21, as shown in Figure 3, is passed between the retaining tapes 15—15 and the under 55 side 14 of the pad.

In adjusting the shoulder pad to the particular wearer, the reinforcing support member 12 is bent to such a position as fits the shoulder and simultaneously provides the desired outline. The retaining tapes are so attached as to be under constant tension and thus considerably increase the frictional contact between the tapes and the under garment strap upon which the pad 10 is positioned. The support member 12, while holding the pad into the desired configuration, also resists or offsets the tension stresses caused by the fastening of the tapes 15-15, and thus prevents the collapsing or distortion which would occur in a case of the soft yieldable pad preferred in this connection.

A number of variations and alterations in the above described embodiment of the invention will become apparent to those skilled in the art. For example, the shape of the pad may be considerably altered and rounded contours imparted thereto as is frequently customary in pads of this type. The reinforcing support member may be altered not only as to material and cross-sectional configuration, but also as to its shape and the manner of support within the pad.

In summary, the present invention resides in the shoulder pad which is capable of retaining its position upon the shoulder of the wearer, is not deformed by the attachment means, and is readily adjustable and conformable to varying shoulder configurations. Furthermore, this improved shoulder pad is light, comfortable, and easily manufactured.

What is claimed is:

1. In a shoulder pad arrangement of the class described, a body member of a roughly triangular contour in plan, one apex portion adapted to be disposed toward the neck of the wearer and an upwardly convex outward margin adapted to be positioned adjacent the outer edge of the shoulder, said body portion comprising a mass

of soft yieldable padding material decreasing somewhat in thickness toward the above mentioned inward apex portion, a fabric covering for said padding, and a reinforcing support member consisting of a pliant, deformable, somewhat resilient wire of substantially endless configuration conforming to the complete marginal contour of the pad including the triangular and the convex outline thereof, said wire being contained within said fabric covering, the whole comprising a conformable shoulder pad which may be molded to the shape of the individual shoulder.

2. In a shoulder pad arrangement of the class described, a body member of a roughly triangular contour in plan, one apex portion adapted to be disposed toward the neck of the wearer and an upwardly convex outward margin adapted to be positioned adjacent the outer edge of the shoulder, said body portion comprising a mass of soft yieldable padding material, a fabric covering for said padding, and a reinforcing support member consisting of a pliant, deformable, somewhat resilient wire of substantially endless configuration conforming to the complete marginal contour of the pad including the triangular and the convex outline thereof, said wire being contained within said fabric covering, the whole comprising a conformable shoulder pad which may be molded to the shape of the individual shoulder.
